(57) **CLAIM**

The ornamental design for a kangaroo play structure, as shown and described.

DESCRIPTION

FIG. 1 is a perspective view of the kangaroo play structure; FIG. 2 is a top plan view of the kangaroo play structure of FIG. 1;

FIG. 3 is an elevation view of the kangaroo play structure of FIG. 1;

FIG. 4 is an elevation view of the kangaroo play structure of FIG. 1;

FIG. 5 is a front elevation view of the kangaroo play structure of FIG. 1; and,

FIG. 6 is a rear elevation view of the kangaroo play structure of FIG. 1.

The broken line showing of environment is for illustrative purposes only and forms no part of the claimed design.
